ABRADING ROLL

Le Roy M. Kubaugh, Akron, Ohio, assignor to
The Firestone Tire & Rubber Company, Akron,
Ohio, a corporation of Ohio

Application April 4, 1949, Serial No. 85,321

12 Claims. (Cl. 51—190)

1

This invention relates to abrading rolls and, more especially, it relates to rotary abrading devices adapted for grinding and polishing operations.

The device of the invention has been found to be particularly advantageous for the abrading of stainless steel sheets, which operation represents one of the highest cost phases in the manufacture thereof. It has long been desired, in the industry, to bring the cost of polishing down to a level comparable with that of ordinary plating. Heretofore, these sheets have been abraded by means of rag buffs firmly clamped together upon an axial mandrel or arbor. These rag buffs consist of stitched fabric discs of individual layers of fabric stitched together, the stitching extending to a diameter somewhat less than the outside diameter of the discs; for example, discs having an overall diameter of eighteen inches are stitched to a diameter of fifteen inches. The discs are necessarily clamped together so firmly upon an arbor that there is little or no resilience to the surface of the buff. The periphery of the assembled fabric disc has abrasive particles, such as grit, adhesively bonded thereto.

In use, a fifteen inch buff or roll is driven at a speed of about 1,000 R. P. M. The buff is reciprocated axially about one and one-half inches. In the grinding operation, the work is reciprocated back and forth in contact with the buff at a speed of about forty-eight feet a minute, the buff rotating always in the same direction, said work being held against the surface of the buff at a controlled pressure. The grinding operation is performed by a dry buff or roll coated with relatively coarse grit; the polishing operation is performed with a buff or roll coated with relatively fine grit, and treated with a fatty lubricant made from animal tissue. The polishing may also be performed with a coarse grit roll which has become worn in the grinding operation. The buffs last approximately two hours on the grinding operation and four hours on the polishing operation, after which they must be removed, turned down slightly, de-greased if necessary, and a new coating of adhesive and grit applied. The buffs lose slightly in diameter upon each reconditioning and when they have been reduced to their stitched diameter, say fifteen inches, the fabric discs are discarded and new buffs built up on the same mandrels from new fabric discs.

The fabric discs must be made from unbleached muslin sheeting which frequently is difficult to procure. The buffs have little or no resilience, especially when coated with adhesive,

2

and in operation make only line contact with the work, with the result that abrading operations consume more time than is desirable. Furthermore, a relatively large portion of each disc ultimately is scrapped, thus resulting in economic loss. It is to the relief of these unsatisfactory conditions that this invention primarily is directed.

The chief objects of the invention are to provide an improved abrading device of the character mentioned for the purposes set forth; to provide an abrading device capable of performing an abrading operation in substantially less time than is required when fabric buffs are employed, to provide an abrading device employing rubber in its structure to provide desirable resilience; to provide an abrading roll of rubber, of long length so constructed that it may be fully molded to provide uniform high density of material, free of voids and air bubbles; to provide an abrading roll that is sectional, thus enabling the roll to be built up to any desirable length and enabling the dynamic unbalance of each section readily to be controlled; to provide in an improved manner for obtaining adequate adhesion of abrasive grit to the surface of the roll; and to enable easier re-dressing of the roll surface for rapid applications of adhesive and grit. In general, the invention aims to effect savings in weight, cost, and maintenance of abrading rolls. Other objects will be manifest as the description proceeds.

Of the accompanying drawings:

Fig. 1 is a perspective view of an abrading roll embodying the invention;

Fig. 2 is a side elevation, on a larger scale, of one of the sections thereof;

Fig. 3 is a section on the line 3—3 of Fig. 2;

Fig. 4 is a side elevation of another type of roll-section embodying the invention;

Fig. 5 is an edge elevation thereof;

Fig. 6 is a section, on a larger scale, on the line 6—6 of Fig. 5; and

Fig. 7 is a view in perspective of a roll-section showing a modification.

Referring to Fig. 1 of the drawing there is shown a sectional abrading roll comprising a plurality of individual abrading drums, each designated as a whole by the numeral 10. The drums 10 are mounted in laterally abutting relation upon an axial arbor or mandrel 11, with which they have driving connection through the agency of suitable keys (not shown). The series of drums 10 are located between end washers, such as washer 12, that are of somewhat smaller di-

ameter than the outside diameter of the drums, and are forcibly urged together by a nut 13 threaded upon a threaded region 14 at one end portion of the arbor 11, there being a spacer member 15 located between the nut 13 and washer 12. The nut 13 and spacer 15 may be duplicated at the opposite end of the arbor if desired, although only a fixed abutment for a washer 12 is required.

As shown in Figs. 2 and 3, drum 10 comprises a metal wheel 18, preferably made of suitable aluminum alloy to have lightness of weight. The wheel 18 comprises a hub portion 19 and a peripheral portion 20, which portions are connected by a central wall 21 located in the medial plane of the wheel and reinforced on opposite sides by a plurality of radial webs 22. The hub 19 is formed with an axial bore 23 in which the arbor 11 is receivable, said bore formed with diametrically opposed keyways 24, 24 that receive the keys (not shown) by which relative rotary movement between the wheel and the arbor is prevented. The outside diameter of the washer 12 is the same as the diameter of the peripheral portion 20 of the wheels. In one embodiment of the invention, this dimension was fifteen inches and the transverse width of the wheel was four inches.

Mounted upon and bonded to the perimeter of portion 20 of wheel 18 is a circumferential layer of non-porous resilient rubber or rubber-like composition 26. The latter is vulcanized in position on the wheel and, in the example, is about one inch in radial thickness. Preferably, the composition 26 has high resistance to the disintegrating effects of oil, grease, and hydrocarbon solvents which may be used in grinding and polishing; accordingly, it consists usually of neoprene or other oil-resistant rubber compound.

Beyond the layer 26 is a second layer 27 of rubber which may be bonded to the layer 26 by concurrent vulcanization therewith. The thin layer 30 of abrasive consists of grit particles dispersed in an adhesive substance and is applied to the outer surface of layer 27 in any convenient manner. For the purpose of bonding the abrasive layer, the material 27 will contain a plentiful dispersion of flock, preferably cotton fibers, oriented in completely random fashion. A suitable material for this purpose is readily obtained from tire cord material (a waste material from ply sheets known as "workaway"), which may be masticated in a Banbury mixer. The resulting fibers, as distinguished from threads, take in the grit adhesive by capillarity and form unusually strong ties between the grit layer 30 and the rubber component. It is this strong bond which is primarily responsible for the long life and efficient performance of the buffers of this invention. Milling of the material for the layer 27 should be kept to a minimum to avoid introduction of directionalization of the fibers, and both mastication and milling should be minimized to avoid such breakdown of the fibers as would destroy their power to hold the grit particles against the separating forces encountered, including centrifugal force.

Although cotton fibers appear to be most effective in coacting with the grit adhesive to furnish a bond, the results are not sensibly different if fibers of other material, rayon for instance, are present in minor proportions. Likewise, the strength of the bond being related to an interlock with fibers rather than to a purely surface adhesion, the proportion of total fibers to total hy-

drocarbon in the fibrous layer will have some bearing on the character of the bond, the latter diminishing in strength as the hydrocarbon approaches 100%. Of course, there is no sharply critical value of proportions where the fibrous layer ceases to be of value for the purposes of this invention, but I have found quite satisfactory results are obtained if the total fibers by weight constitute from 30 to 40 percent of the total vulcanizate constituting the fibrous ring.

Each pair of rubber rings 26 and 27 is placed on the peripheral portion 20 of a wheel 18 and vulcanized in an ordinary, pressure, steam platen press. Since there is a tendency of rubber to shrink upon vulcanization, the outer portion of uncured rings 27 in the uncured state will preferably have a greater width than the peripheral flange 20. In fact, the outer width of rings 27 when cured should be somewhat greater than the width of flange 20 so that the outer portion of the rings 27 will be compressed slightly on assembly and thus preserve an unbroken grinding surface.

Prior to each application of the grit surface, the fiber nap is brought up on the surface of rings 27 by treatment with a wire wheel or similar roughing tool.

In practicing the present invention, it has been preferred to employ, as an adhesive, animal glue, silicate of soda, synthetic resinous adhesives, or rubber cement. Regardless of the adhesive employed it has been observed that excessive heat will cause a breakdown thereof. With the present construction it has been possible to dissipate heat to an extent which will eliminate this breakdown by providing vanes in the walls of the metal wheels which will bring about a forced draft axially of the drum. This is shown in Fig. 7 where the walls 28 of the wheel are slanted from the plane of the wheel and have an opening 29 through which the forced stream of air may pass, as in the case of a fan blade. Other types of heat dissipation, such as water cooling, which were not obtainable with the stacked, fabric discs of the prior art, are also possible in the present construction.

Although the prior practice has been to provide intermittent, relative sidewise shift between the buffer and the sheet being abraded, yet if any considerable cleavage should occur at the peripheral line between adjacent individual drums, scoring will occur.

Such effect is eliminated by the drum structure shown in Figs. 4 to 6, wherein the side edges of the outer ring 31 and the side edges of the upper part of inner ring 32 are staggered outwardly, as at 33, and inwardly, as at 34, about the edges of the wheel 18 as a mean position, the lower part of the ring 32 coinciding with the outer surface of wheel 18. For the purposes above stated, the width of the outer rings 31, 32, at any point, will be somewhat greater than that of part 20 of the wheel 18.

From the foregoing it will be seen that there is provided, by the present invention, an abrading and polishing wheel which accomplishes a given amount of work in a much shorter time than has been possible heretofore; which costs considerably less than prior devices; which is constructed from materials ordinarily considered as waste and of which there is an ample supply; which has a longer life than prior devices; functions for a longer period without maintenance interruptions, and results in less waste at the end of its useful life. In addition, the buffer of this

invention is resistant to oils and greases, desired for use in the abrading operation but not possible with the prior fabric discs, and is capable of being cooled during operation. Furthermore, whereas in the prior devices it was almost an economic necessity that an abrading wheel, after being worn, be shifted to serve as a polisher, it is economically possible with the present wheels to adapt each to its particular service and thus attain more uniform and satisfactory results.

While the invention has been illustrated as a buffer composed of sectional units, this form is dictated by the exigencies of molding practice and is preferable as facilitating and economizing replacement of parts. However, the buffer drum may be constructed in one piece if desired. Likewise, the drum is not limited as to size and each of the sections 10, for instance, may be individually employed as a buffer for small scale work.

The term "rubber" used herein, and in the claims, has reference more particularly to certain physical properties inherent in natural or synthetic rubbers or plastics with polymeric structure whereby they are resilient in the sense of being readily deformable under pressure, are liquid impervious and may be milled, masticated, and vulcanized into permanent form.

The prime function of the first layer of rubber 26 is one of cushioning, which, among other things, permits a working surface for the abrading operation as distinguished from a line contact. The composition, location and dimensions of this layer may vary within wide limits, being dictated by the requirements of each abrading tool. The composition of the rubber matrix in the working layer 27 may also vary considerably.

After the abrasion layer 30 has been worn smooth beyond the point of usefulness, it can be removed with an appropriate tool in a manner heretofore conventional in the art. In this process a small outer layer of the rubber part 27 is removed, exposing fresh, bonding fibers, and the new grit layer is applied. Repeated renewal of the grit layer will, in time, result in removal of all of the rubber portion 27. At such time, the initial layer of rubber 26 is removed and new layers similar to 26 and 27 are vulcanized in place.

Various other modifications of the invention will be apparent to those skilled in the art and, therefore, it is not to be construed as limited except as shall appear from the spirit and scope of the appended claims.

What is claimed is:

1. An abrasive tool comprising a rigid central shaft, a series of rigid rings keyed to said shaft, a first ring of resilient material surrounding each of said rigid rings, a second ring of resilient material surrounding each of said first resilient rings, said second resilient rings comprising a dispersion of fibers in a rubbery material, and an outer coating of grit on said second resilient ring, adhesively bonded to the fibers at the surface zone thereof.

2. An abrasive tool comprising a rigid shaft, a series of rigid rings keyed to the shaft, a first resilient ring surrounding each of said rigid rings, a second resilient ring surrounding each of said first resilient rings, said second resilient rings each comprising a rubbery material having a dispersion of organic fibers, said second resilient rings each having a width greater than the maximum width of the rigid ring, and means on the shaft adapted to compress the series of rigid

rings axially whereby the said second rings are pressure-sealed at all interfaces.

3. An abrasive tool comprising a rigid shaft, a series of rigid rings keyed to the shaft, and a ring of rubbery material surrounding each of said rigid rings, said rings having mating, serrated peripheral edges.

4. An abrasive tool comprising a rigid shaft, a series of rigid rings keyed to the shaft, a first resilient ring surrounding each of said rigid rings, and a second resilient ring surrounding each of said first resilient rings and comprising a dispersion of fibers in a rubbery material, and adapted to receive, in bonded relation, a coating of grit dispersed in an adhesive substance, the outer peripheral edges of said rings having mating serrations.

5. An abrasive tool comprising a rigid shaft, a series of rigid rings keyed to the shaft, a ring of rubbery material having a dispersion of organic fibers and surrounding each of said rigid rings, abrasive means adhesively bonded to the outer surface of each of said rings of rubbery material, and blade means in the body of said rigid rings whereby an air draft is provided lengthwise of the tool.

6. A rotary, abrasive tool comprising a rigid, base roll, an intermediate roll layer of resilient material, and an outer roll layer of non-porous rubber containing throughout a random dispersion of organic fibrous material in mutually spaced relation with the rubber predominating in volume, protruding ends of said fibrous material adapted to securely bond an outer adhesive layer containing abrasive grit, and said outer layer being of substantial radial depth whereby said outer layer may be successively ground to present fresh surfaces with extending fibers for bonding with newly applied adhesive layers.

7. A rotary, abrasive tool comprising a rigid, base roll, a first roll layer of resilient material on said base roll, a second roll layer on said first layer comprising a random dispersion of fibers, in mutually spaced relation, in non-porous rubber with the rubber predominating in volume, and an extreme outer layer of abrasive material in an adhesive vehicle which is bonded to said second layer and the protruding ends of fibers contained therein, said tool adapted for successive grinding of said second layer to provide fresh fiber ends for successive attachment of renewal layers of grit.

8. A rotary, abrasive tool comprising a rigid, base roll, an intermediate roll layer of resilient material, and an outer roll layer of non-porous rubber containing throughout a random dispersion of cotton fibers in mutually spaced relation with the rubber predominating in volume, protruding ends of said fibers adapted to securely bond an outer adhesive layer containing abrasive grit, and said outer layer being of substantial radial depth whereby said outer layer may be successively ground to present fresh surfaces with extending fibers for bonding with newly applied adhesive layers.

9. An abrasive tool comprising a rigid, central shaft, a series of rigid rings keyed to said shaft, a first ring of resilient material surrounding each of said rigid rings, a second ring surrounding each of said first rings, said second ring comprising non-porous rubber containing throughout a random dispersion of fibers in mutually spaced relation, with the rubber predominating in volume, protruding ends of said fibers resulting from a roughing operation adapted to se-

surely bond an outer adhesive layer containing grit, and said second rings being of substantial radial depth whereby to be successively ground to present fresh surfaces with slightly extending fibers for bonding with newly applied adhesive layers, and means on said shaft holding said second rings in close, side-by-side relation.

10. As an article of manufacture, an abrasive tool comprising a rigid ring, a second ring received on said first ring, said second ring comprising a body of non-porous rubber containing throughout a random dispersion of fibers in mutually spaced relation, with the rubber predominating in volume, slightly protruding ends of said fibers which result from a roughing operation being adapted to securely bond an outer, adhesive layer containing abrasive grit, and said second ring being of substantial, radial depth whereby said second ring may be successively ground to present fresh surfaces with protruding, fiber ends for bonding with newly applied adhesive layers.

11. As an article of manufacture, an abrasive tool comprising a rigid ring, a second ring received on said first ring, said second ring comprising a body of non-porous rubber containing throughout a random dispersion of fibers in mutually spaced relation, with the rubber predominating in volume, a layer of adhesive, containing grit, bonded to said second ring and to slightly protruding ends of said fibers which result from a roughing operation on said second ring, and said second ring being of substantial, radial depth to permit successive surface renewals by grinding operations.

12. The method of improving the grit-holding

power and lengthening the life of abrasive wheels which comprises providing, on a rigid roll, a layer of non-porous rubber having a random dispersion of fibers in mutually spaced relation, with the rubber predominating in volume, roughing the outer surface of said layer so that ends of the fibers protrude slightly from the surface, and applying to the thus treated surface a coating of adhesive containing a dispersion of grit.
